UNITED STATES PATENT OFFICE

162,082

COMBINATION CAN AND BOTTLE OPENER

Carl G. Preis, Forest Hills, N. Y., and William Pechy, Manasquan, N. J., assignors to American Can Company, New York, N. Y., a corporation of New Jersey

Application May 2, 1949, Serial No. 2,386

Term of patent 14 years

(Cl. D22—2)

To all whom it may concern:

Be it known that we, Carl G. Preis, a citizen of the United States, residing at 60 Greenway South, Forest Hills, county of Queens, and State of New York, and William Pechy, a citizen of the United States, residing at P. O. Box 77, Manasquan, county of Monmouth, and State of New Jersey, have invented a new, original, and ornamental Design for a Combination Can and Bottle Opener, of which the following is a specification, reference being had to the accompanying drawing, forming a part thereof.

Fig. 2 is a bottom perspective view; and

Fig. 3 is a side elevational view.

We claim:

The ornamental design for a combination can and bottle opener, as shown.

CARL G. PREIS.
WILLIAM PECHY.
